UNITED STATES PATENT OFFICE.

GLENN U. ANGEVINE, OF CHICAGO, ILLINOIS, ASSIGNOR TO THE G. U. ANGEVINE COMPANY, OF CHICAGO, ILLINOIS, A CORPORATION OF ILLINOIS.

DRAPEY HANGER.

Application filed November 8, 1924. Serial No. 748,521.

This invention relates generally to drapery hangers and in particular to improvements in a drapery hanger of the type disclosed in my prior Patent No. 1,451,754. Heretofore, drapery hangers have been provided as unitary structures of both the single and duplex types. Especially, those hangers of the duplex type, which are adapted for securing draperies to both sides thereof, are accompanied by many disadvantages in use. A drapery hanger is usually provided with one or more side members, to which the drapery may be sewed. In the duplex type the forms heretofore provided make the sewing an inconvenient operation. Besides this disadvantage, it is usually necessary to remove the supporting rod in order to put up or take down the drapery and thereafter if the drapery is to be cleaned, it is necessary to cut the stitches which attach the drapery to the hanger. The present invention aims to overcome all these difficulties and to provide a hanger having many other advantages.

The primary object of this invention is to provide a hanger which is composed of several sections, the side members of the hanger to which the draperies are to be attached being removable from the main supporting section, so that the drapery may be sewed to the separate members before the members are assembled with the supporting section.

Another object is to provide a hanger with substantially flat detachable side members so that the same may be left attached to the drapery without danger of injury thereto in the cleaning operation.

A further object of the invention is to provide a hanger of such a construction that it is not necessary to remove the supporting pole in order to remove the drapery.

A further object of the invention is to provide a curtain hanger with removable side members and to provide locking means to secure said members in attached position.

Still another object is to provide the removable side members with a suitable latch which, in the assembled condition of the hanger, makes it a substantially rigid unitary structure.

Still another object is to provide hangers which in unassembled condition may be compactly arranged in a relatively small space for shipping or storage purposes.

Other and ancillary objects and advan-

tages will be apparent from the description hereinafter given of an exemplary embodiment of my invention, as shown in the accompanying drawings in which—

Figure 1 represents a duplex hanger in the assembled position placed on a supporting rod.

Fig. 2 represents the hanger of Fig. 1 in the unassembled position showing the two faces of the side members.

Fig. 3 represents the longitudinal section along the line 3—3 of Fig. 4.

Fig. 4 represents a section along the line of 4—4 of Fig. 1.

Referring more particularly to the drawings, the numeral 8 represents a bridge member substantially U-shaped having the side arms 9 and 10, between which a suitable roller 11 is mounted. The roller comprises a cylinder which has been concaved in part 70 to conform to the shape of a supporting rod 12, thereby insuring centering of the hanger on the rod. The roller runs axially loose on a shaft 13 which is held fast in the side arms 9 and 10. Suitable spacers or collars 80 14 and 15 are provided between the roller ends and the side arms 9 and 10. The outside face of each arm and the end of the pin 13 are flush and flat, the foregoing structure thus providing a supporting section for 85 the hanger. The side arms 9 and 10 are so constructed with relation to the side members which carry the drapery that said members may be removably mounted upon this supporting section. In the present instance 90 the U-shaped piece 8—9—10 is a single strip originally of uniform width. In order to provide retaining means in the form of side projections or flanges on the arms 9 and 10, a portion of the bridge 8 adjacent each arm 95 is notched at each side as shown at 16 and 17 (Fig. 4). The notches constitute the edges 18 and 19 of the strip as projections relative to the narrow portion 20 formed by the notching process.

The movable members are preferably provided as flat strips and are adapted to cooperate with the retaining means of the supporting section. The retaining means on the strip is adapted to clinch the above described projections 18 and 19 and the strips are accordingly provided with a suitable structure for that purpose. In the present instance the parts are brought into clinching relation by the sliding action of the 110

strips over the projections through the notches 16 and 17. In Fig. 2 the side strip 22 at the left is shown presenting its inside face, of which the area 23 abuts the arm 9 upon its outside flat face. Hook shaped flanges 24 are formed at the sides of the area 23. The hook portions form grooves which receive the projections 18 and 19 in the sliding action above described. The structure so far described permits the sliding of the hooked flanges 24 onto the projections 18 and 19. Suitable means are provided to limit the sliding action and to retain the strip in a fixed relation to the bridge member. The sliding is limited by the provision of an abutting shoulder 25 formed just above the area 23 in the strip 22, the shoulder meeting with the narrowed portion 20 of the bridge 8. In addition a suitable lock or catch may be provided to prevent accidental separation of the members. As indicated in the drawings a spring member 26 is secured to the strips 22 by an eyelet 27. A beveled V portion 28 is formed in the spring which projects through a hole 29 in the strip at such a position that it latches against the end 30 of the side arms 9 or 10. Besides the eyelets 27, other holes such as 31 and 32 are provided in the strips for sewing the curtain or drapery thereto.

In use it is necessary first to sew the several strips to the drapery. The fact that each strip is detachable permits of the drapery being sewed to each one without interference from the opposite strip. And furthermore, because of the substantially flat form in which each strip is constructed the sewing to the individual strip is relatively easy and convenient when compared to the older types. In placing the curtain hangers upon the supporting rod 12, the latter need not be removed. The roller 11 is first positioned on the rod and the several strips with the drapery attached are slid into position where they become automatically locked by the catch 26. In removing the draperies the process is reversed, it being, of course, necessary to move the catch 26 for releasing the strips. If the draperies are to be cleaned the flat form of the strips permits that they be left on the curtains if desired without danger of injury to either, and without the otherwise necessary labor of removing the curtain from a unitary hanger and again sewing it thereto when replaced. Aside from the utilitarian standpoint a commercial advantage obtains when a large number are to be shipped, since in the unassembled condition they may be readily packed as parts in a much smaller space than would be required for the same number of the older unitary devices.

It will be observed that I have provided an improved hanger which is provided with removable strips of a particular character,

and that further the removable strips are arranged to be locked in place against accidental separation which frequently occurs when the curtains are jerked or quickly moved on the rod.

In the foregoing description, it is to be understood that the specific and detailed structure which has been set forth in no way limits the invention to the exemplary embodiment thereof. To those skilled in the art many equivalent structures may be used falling within the contemplation of the invention. It is the object of the appended claims to set forth the invention in its broadest scope limited only by the prior art.

I claim as my invention:

1. A drapery hanger comprising, in combination, a U-shaped supporting member, a roller bearing in the sides of the U-shaped member, a member removably attached to each side of the U, each member being adapted for securing draperies thereto, and means to automatically engage each member in attached position.

2. A drapery hanger comprising, in combination, a U-shaped supporting member, means carried by said U movably to support said member on a longitudinal support, a side member adapted for securing a drapery thereto, cooperating means on the U and the side member for removably attaching the member to the supporting member, and means to lock each member in attached position.

3. A drapery hanger comprising, in combination, a U-shaped supporting member, means carried by said U movably to support said member on a longitudinal support, a side member adapted for securing a drapery thereto, cooperating means on the U and the side member for removably attaching the member to the supporting member, and interlocking means on said U and said side member for automatically locking and holding said parts in fixed relation.

4. A drapery hanger comprising, in combination, a main supporting member adapted to move longitudinally along a fixed support, a side strip adapted to be attached to a drapery, the main supporting member having opposing grooves cut therein, hooked flanges on the side strip adapted to engage in said grooves whereby to bring the two members into a rigid clinched relation.

5. A drapery hanger having, in combination, a main supporting member adapted to engage a suitable support, a side member removably attached thereto and adapted to be secured to a drapery, and means to lock said member in attached position.

6. A drapery hanger comprising, in combination, a main supporting section adapted to engage a support, opposing side sections removably attached to said supporting section, said side sections being adapted for

securing draperies thereto on opposite sides of the support, and means to automatically interlock said side sections in attached position.

5 7. A drapery hanger comprising, in combination, a main supporting member adapted to engage a support, opposing side strips removably mounted on said member, said strips being adapted for securing draperies 10 thereto, and cooperating means on said supporting member and said side strips to lock said strips in mounted position.

8. A drapery hanger comprising, in combination, a main supporting section adapted 15 for movement longitudinally along a suitable support, said section presenting a substantially flat face at one side thereof, a side strip adapted for carrying a drapery, hooked flanges on said strip forming opposing 20 grooves between the face of the strip and the hooked portion of the flanges, opposing projections on the main supporting member adjacent its flat side face, said projections being adapted to slide into said grooves for 25 mounting the strip on the supporting section by a sliding action, and means to limit the sliding action.

9. A drapery hanger comprising, in combination, a U-shaped member, a roller there- 30 in carried by the arms of said U to give rolling support to the hanger on a suitable means, opposing projections on each side arm of the U member, a removable side strip

for each arm having a portion adapted to abut the outer face of said arm, hooked 35 flanges on said strips adapted to receive said projections in a sliding action of the strip onto the arm, and a shoulder formed in said strip to abut the U-shaped member whereby to limit the sliding action. 40

10. A drapery hanger comprising, in combination, a rigid supporting section having flat side faces at each end thereof, flanges projecting from said side faces, a strip slide- 45 able onto each end, said strips having grooves therein to receive said flanges, and means to limit the sliding action.

11. A drapery hanger comprising, in combination, a rigid supporting section having flat side faces at each end thereof, flanges 50 projecting from said side faces, a strip slide- able onto each end, hooked flanges on said strip adapted to clinch said first named flanges in a sliding action of said strips onto the supporting section, and means to limit 55 the sliding action.

12. A drapery hanger comprising, in combination, a rigid supporting section, a strip adapted to be secured to said section at one end thereof, interlocking means associated 60 with said end and said strip to automatically lock and hold said end rigidly secured to said strip in a predetermined relation.

In testimony whereof, I have hereunto affixed my signature.

GLENN U. ANGEVINE.
